UNITED STATES PATENT OFFICE.

HILARION DE ESCOBALES, OF NEW YORK, N. Y., ASSIGNOR TO H. ESCOBALES CO. INC., OF NEW YORK, N. Y., A CORPORATION OF NEW YORK.

METHOD OF AND APPARATUS FOR PACKAGING ARTICLES.

1,391,173.

Specification of Letters Patent. Patented Sept. 20, 1921.

Application filed June 8, 1917. Serial No. 173,558.

To all whom it may concern:

Be it known that I, HILARION DE ESCOBALES, a citizen of the United States, residing at New York, in the county of New York and 5 State of New York, have invented new and useful Improvements in Methods of and Apparatus for Packaging Articles, of which the following is a specification.

This invention relates to the packaging 10 of articles, pertaining more particularly to apparatus for providing the packaging operations and methods of manipulating the wrapping or inclosing elements.

While the invention is adapted for the 15 packaging of commodities of different types, the embodiment shown is designed more particularly for the packaging of tobacco products, especially of cigarettes or little cigars, although, as hereinafter pointed out, 20 the apparatus may be employed for the packaging of other tobacco products, such, for instance, as plug tobacco. For the purpose of illustrating the invention, it is assumed that the commodity to be packaged 25 is a predetermined number of cigarettes.

In packaging tobacco products certain 30 essential features must be considered in producing a package which is neat and attractive in appearance and which will provide for proper service conditions.

For instance, one of the features is to 35 maintain, as far as possible, the characteristic qualities of the product present at the time of manufacture, even though the package 40 does not reach the consumer for a considerable length of time. The package should, therefore, be of a form which will tend to reduce as far as possible access of air and moisture to the product during this 45 period. In the present invention this feature may be taken care of by employing a wrapper which is folded about the commodity to produce a closely-wrapped packet, and then positioning this packet within an outer container. If desired, the wrapper may 50 be of material having air and moisture-proof qualities, as for instance, tin foil or a composite tin foil structure.

Another feature is the requirement that 55 the package carry its Government stamp in such manner that the stamp must be mutilated when the package is opened for use by the consumer.

In the invention herein disclosed, this effect is produced by partially surrounding 55 the packet with the revenue stamp in advance of insertion of the packet into the container, and then securing another portion of the stamp to an exposed face of the container in such manner that the packet cannot be removed from the container without rupturing the stamp. While complying 60 with the Government requirement in this manner, the particular manner in which the stamp is secured in position also enables a 65 stamp to act as a means for maintaining the packet in position within the container regardless of whether or not the container closing flap is in its closed position, the closing flap acting to retain the packet in 70 its inclosed position after the stamp has been ruptured.

Another and important feature is the cost 75 of production of the package, it being readily understood that tobacco product packages are generally of a predetermined standard and marketed at comparatively low price. Hence, where, in order to meet the various essentials, the cost of packaging is materially increased, the question of cost 80 of production of the package becomes of material importance in the ability to market the product. Where the packaging involves a number of operations, requiring different mechanisms and more or less manipulation 85 manually, the cost of labor becomes an important item. The present invention meets this condition by completing the packaging operation, including the wrapping, the stamp application and inclosing of the 90 packet within the container, in a single apparatus in which the various operations are provided in automatic sequence, the cigarettes being segregated from bulk supply into charges of the desired number of 95 cigarettes and forming the product to be packaged, the wrapper being preferably supplied from a roll and cut into proper length, the stamps being of the usual strip-like form supplied by the Government, and 100 the containers being in blank form, the apparatus providing a series of successive

steps of manipulation of one or more of the parts of the package with the result that the charge of cigarettes selected is discharged from the apparatus in a completely 5 packaged form; as a result, it is necessary only for the operator to prevent either of the sources of supply of the several parts of the package from becoming empty. Obviously, therefore, a single operator may take 10 care of one or more machines, thus reducing the labor cost to a minimum as well as providing for a largely increased output.

With these general objects in view, together with other objects which will be 15 readily understood as the invention is hereinafter disclosed, said invention consists in the improved construction and arrangement of parts, together with methods of manipulation, all as hereinafter fully described, 20 illustrated in the accompanying drawings, and more particularly pointed out in the appended claims.

In the accompanying drawings, in which similar reference characters indicate similar 25 parts in each of the views,—

Figure 1 is a top plan view showing one embodiment of apparatus for carrying out the invention, parts being broken away or omitted for clearness.

30 Fig. 2 is a longitudinal sectional view taken on line 2—2 of Fig. 1.

Figs. 3 and 4 are cross-sectional views taken on line 3—3 and 4—4 respectively of Fig. 2.

Fig. 6 is a view of a portion of the elements of Fig. 5, showing certain elements in a different position.

40 Figs. 7 and 8 are fragmentary detail sectional views showing the manner in which the cigarettes are placed in position for wrapping.

Fig. 9 is a plan view of a portion of the 45 machine.

Figs. 10 and 11 are sectional views taken on lines 10—10 and 11—11 respectively of Fig. 9.

Fig. 12 is a sectional view taken on line 50 12—12 of Fig. 11.

Fig. 13 is a face view of a cam for operating the main plunger.

Fig. 14 is a detail side elevation of a stamp feeding mechanism which may be 55 employed.

Fig. 15 is a side elevation showing portions of a blank feeding mechanism.

Fig. 16 is a top plan view of parts shown in Fig. 15.

60 Figs. 17 to 30 inclusive show more or less diagrammatically successive stages in the wrapping, stamp-applying and container-inclosing operations.

To enable a better understanding of the 65 apparatus to be had, I will first give a brief

description of the successive steps employed in producing the package (Figs. 17 to 30).

The cigarettes to be packaged are first segregated from the bulk into row formation and delivered to a carrier in such formation, 70

the carrier then being shifted to a position where the charge is introduced into the path of travel of a plunger. The charge is then advanced by the plunger into contact with a wrapper blank (previously fed into position by suitable feed mechanism operating

75 to advance a web of the wrapper-forming material and severing the web at the proper point to produce the blank)—Fig. 17—the advance of the plunger then carrying the

charge and the wrapper into a horizontally extending folding channel which is adapted to fold the non-contacting portions of the blank on to the top and bottom faces of the charge and turn-in advance portions of

80 the wrapper on to the sides of the charge, Fig. 18. The charge and wrapper in this form are carried through the folding channel into a vertically movable carrier positioned at the end of the channel, the pro-

85 tecting rear end of the wrapper remaining within the channel, the portion of the wrap-

per in advance of the rear of the charge and the charge itself passing into the carrier.

The carrier is then lowered, withdrawing 90 the projecting end of the wrapper and fold-

95 ing it upwardly against the rear of the charge, (Fig. 19) this movement of the carrier bringing it into alignment with a sec-

ond folding channel and into the path of movement of a second plunger which has

100 its advancing movement in a direction op-

posite the advance movement of the first plunger. At this stage, the portion of the

105 wrapper previously at the rear becomes the advance of the packet, and the advancing movement of the second plunger carries the

packet into the second folding channel

110 which acts to fold the upwardly extending end of the wrapper on to the top of the charge—Fig. 20—preferably to overlap the

115 opposite end of the wrapper, this folding being followed by the turning-in of ad-

vance portions of the wrapper to produce end flaps at the ends of the packet—Fig. 21.

120 As the packet continues its advance move-

ment (due to the advance movement of the second plunger) the top end flaps are first

folded down (Fig. 22), the lower end flaps

then being turned up to overlap the top

125 flaps (Fig. 23), completing the wrapping

of the charge, thus placing those portions of the wrapper ends which extend into the end flaps in an underlying relation in the end flap formation. The completion of the ad-

ment being such that during the advance movement of the third plunger, one of the flap-closed ends of the packet becomes the advance end of the packet. Advance of the third plunger advances the packet into contact with the adhesively-coated face of a Government stamp—Fig. 24—previously placed in position with its adhesive-coated face ready to be adhesively secured to the 10 packet. The advancing packet then moves into a channel, carrying the stamp into the channel in such manner as to cause one end of the stamp to extend on to the upper face of the packet—preferably over the overlying 15 ends of the wrapper—the opposite end of the stamp being carried along the under face of the packet, the remainder of the stamp, with its adhesive-coated face uppermost, projecting in rear of the packet (the packet 20 portion of Fig. 25). Further advance of the packet brings its advance end—with the stamp overlying such end—into contact with a container blank (Fig. 25) previously positioned by suitable feeding mechanism, the 25 contact being at that point of the container blank which will, in the complete package, form the bottom of the package. As the packet continues its advance, it passes into a channel which acts to carry the opposite 30 ends of the container on to the top and bottom faces of the packet and in overlying relation to the portion of the stamp affixed to the wrapper, and carries the side flaps of the portion of the blank at the top of 35 the packet into contact with an adhesive-applying mechanism and then into operating relation with devices for turning these adhesive-coated or strip flaps downwardly (Fig. 26), the continued movement then 40 bringing the side flaps of the under container portion into proper relation with mechanism for turning these flaps upwardly into contact with the adhesive of the upper flaps—Fig. 27—the completion of the 45 advance movement of the third plunger placing the container-inclosed packet at the upper end of a well with the end laps and the closing flap of the container extending into such channel. Upon retreat of the third 50 plunger, operating fingers are manipulated to carry the end laps inward—Fig. 28—after which a vertically reciprocating plunger moves the package downwardly within the well a distance equal to the thickness of 55 the package, this movement acting to turn up the closing flap over the end of the packet, carrying the stamp into contact with such packet end, and leaving exposed, above the top plane of the upper face of the container, a portion of the container closing 60 flap and a projecting end of the stamp (Fig. 29), these elements being in the path of travel of the succeeding container while being positioned over the well, such succeeding 65 container turning down these projecting

portions, thus extending the stamp over the upper face of the container with the adhesive face of the stamp in contact with the container, the extreme end of the closing flap overlying the stamp—Fig. 30. As the 70 downward movement of the succeeding container is made, pressure will be applied to the overlying and exposed portion of the stamp, thus affixing the stamp to the container face, and completing the package 75 formation.

This sequence of operations first applies the wrapper on to the charge in such manner as to practically render it air and moisture-proof, especially if the wrapper is 80 formed of material having air and moisture-proof qualities, the stamp then applied to the wrapper charge in a manner to partially surround it in such way as to prevent opening of the wrapper without mutilating 85 the stamp, and the container folded about the stamped packet, the opposite stamp end being then secured to an exposed face of the container. As a result, the stamp is not only exposed and located in such manner as 90 to prevent movement of the packet out of the container without mutilation of the stamp, but the manner in which the stamp is applied causes it to act as a means for retaining the packet in position within the 95 container, the stamp extending across the path of movement of the free end of the closing flap in such manner as to prevent such end from being introduced into a position between the container face and the 100 wrapper. The completion of the package leaves this closing flap entirely exposed, but folded over to protect that portion of the stamp which is free from adhesive connection with either wrapper or container, the 105 closing flap, however, being free to move so as to expose the outer wrapped end and its overlying stamp, so that inspection of the integrity of the package can be had without 110 affecting the stamp itself. When it is desired to use the charge, the stamp is ruptured which permits the wrapped charge to freely pass out of the container. After the stamp has been ruptured, the closing flap may be 115 passed into closing position between the container face and the wrapper, thus enabling the package to be placed in a convenient form for carriage in the pocket.

For purposes of description, the formed and positioned charge is indicated at A, the 120 wrapper at W, the stamp at S, and the container at C.

In describing the apparatus for producing these results, the description will, as far as possible, follow this step succession.

As heretofore indicated, the apparatus disclosed is designed to produce the package automatically, the cigarettes being introduced in bulk, the material of the wrapper supplied in the form of a roll, and the 130

stamps and container blanks being in pile formation, the stamps and blanks being preferably fed from the bottom of the pile, enabling the piles to be replenished while 5 the machine is in operation.

The various mechanisms are mounted on a suitable frame structure or structures, indicated generally at 50, the several mechanisms being operatively connected to a rotatable shaft 51, driven in suitable manner, indicated by the fast and loose pulleys 52, the fast pulley being operatively connected to the shaft 51. 53 indicates a hopper into which the cigarettes are introduced in bulk, 10 the bottom of the hopper having a plurality of vertically extending partitions 54 forming spaces of a width sufficient to receive individual cigarettes, these spaces forming passage ways for these segregated cigarettes. 15 As will be understood, the number of spaces will depend on the number of cigarettes which it is desired to place in the width of the container. For instance, where the package is adapted to carry ten cigarettes, 20 the arrangement may be such as to provide for ten spaces,—in which case the cigarettes will be in a single row—or five spaces may be provided and the cigarettes be packaged in the form of two rows of five each. The vertical 25 length of the partitions is preferably such as to form passage ways of a vertical length greater than the number of rows of cigarettes in a package, the cigarettes collecting in these passageways, passing out of 30 the passageways in a manner presently described.

To aid in segregating the cigarettes from the bulk supply and distributing them into the passage ways or channels referred to, 35 I employ a distributing plate 55 having an opening 55^a of a length substantially equal to the over-all length of the inlet ends of the channels, this plate 55 having a reciprocating movement in the hopper above the 40 partitions. This reciprocating movement is had through the action of a crank 56^a carried by a vertical shaft 56 connected by gears 56^b to shaft 51, crank 56^a being connected to plate 55 in suitable manner as by 45 a link 56^c.

The hopper is located above a carrier which is shown in the form of a dial 57, the latter being located above a stationary plate 58, said plate forming the bottom of 50 a plurality of charge-receiving pockets 57^a formed in the dial 57, the portions of these pockets carried by the dial having open tops and bottoms. The pockets are spaced apart about the periphery of the dial, the spacing, in the embodiment shown, producing 55 four pockets, each pocket having partitions corresponding in position to partitions 54, so that when a pocket is located below the channels for the cigarettes, the channels will 60 be practically continuous to the bottom of 65

the pockets, the pockets having a depth sufficient to receive a layer or layers, depending on the number of rows of the cigarettes to be contained in a single package, the cigarettes being supported on the plate 58. 70

The cigarettes are preferably received by the dial in one position of the latter and discharged from the dial at a different position of the pocket, a preferred arrangement being to locate the receiving and discharging stations on a line corresponding to a diameter through the dial, the dial making a half revolution between the receiving and delivery stations. Obviously, this may be varied to meet individual conditions, the 80 arrangement shown being such as to provide for economy in space, permitting other operating parts to be brought into relatively close relation, thus providing for minimum travel of parts and a compact arrangement 85 of mechanisms.

The dial, in the embodiment shown, is moved intermittently, being given a quarter revolution when moved. The mechanism for producing this dial movement is operated from shaft 56, the latter carrying a disk 59 having a flange 59^a and a pin 59^b adapted to cooperate with a complementary member 60 to produce a mechanism of the Geneva stop type, member 60 being mounted on a stud shaft carrying a gear 61 which is adapted to drive a gear 62 on dial shaft 57^b through an intermediate gear 63. By this arrangement each revolution of disk 59 operates member 60 to advance the dial a 100 quarter revolution, this action taking place while pin 59^b is in engagement with member 60, the latter being held stationary by the flange 59^a during the remainder of the disk revolution. Consequently, the dial will 105 dwell for a predetermined period after each of its movements. The cigarettes are received into that pocket below the hopper at the time of dwell, and at the same time, the cigarettes in the diametrically opposite 110 pocket will be discharged from the pocket, plate 58 being so arranged as to eliminate its cigarette-supporting relation to the pocket which is located in discharging position.

Positioned below the plane of plate 58 below the point of discharge of cigarettes is a yieldable plate 64 which normally forms a supplemental bottom to the pocket when the pocket is in discharging position. Plate 120 64 is carried by a pin 64^a, the lower end of which is provided with a member 65 adapted to cooperate with a stop member 65^a carried by the frame of the machine, members 65 and 65^a co-operating to limit the upward 125 travel of plate 64. Pin 64^a also carries a spring 66 which is interposed between plate 64 and an arm 67 carried by a vertically reciprocating rod 68, the movements of said rod being controlled by a cam 69 mounted 130

on shaft 51, a spring 67^a, connecting arm 67 and the machine frame acting to retain operative contact between rod 68 and cam 69, the latter being arranged to cause the 5 rod to reciprocate vertically.

70 indicates an arm carried by rod 68 above the plane of dial 57, said arm carrying a depending member 71 adapted to act as a plunger for moving the cigarettes out 10 of the dial pocket, said member having a configuration adapted to produce this result. In addition, member 71 carries a pair of depending pins 71^a having a length extending below the lower plane of the plunger, the dial having additional openings through which pins 71^a may pass into contact with plate 64.

Cam 69 is so formed and timed that during the period when cigarettes are not being 20 discharged from the dial pocket, plate 64 is in position to form the bottom of a pocket, while plunger 71 is located above the plane of the dial, the result being that the dial is free to move to shift the pockets.

25 When the pocket is brought to proper position by the dial actuating mechanism, cam 69 permits rod 68 to move downwardly under the action of spring 67^a, this movement of the rod carrying arms 67 and 70

30 downwardly from the position shown in Fig. 3 to that shown in Fig. 7, this movement bringing pins 71^a into contact with plate 64, and the arm 67 downwardly into contact with member 65 (arm 67 being nor-

35 mally positioned above member 65), thereby placing an increase of tension on spring 66. This downward movement of the plunger has also brought its remaining fingers into contact with the cigarettes and caused

40 the latter to pass downward on to plate 64 as shown in Fig. 7, plate 64 remaining in position due to the tension of spring 66. Further downward movement of rod 68 causes arm 67 to move member 65 out of con-

45 tact with stop member 65^a, thus lowering plate 64 through this action and by the action of pins 71^a which are in contact with the upper face of plate 64 at this time, the result being that when these parts reach

50 the position shown in Fig. 8, the cigarettes will have passed entirely from the dial and will have been brought into closer relationship with each other by the action of a pair of inclined faces 72 between which the

55 outer cigarettes are carried during this discharging operation. As will be understood, no undue pressure will be placed on the cigarettes during this discharging operation for the reason that pins 71^a produce a

60 fixed distance between plate 64 and the lower ends of the plunger fingers; in addition, the downward movement of rod 68 is provided by a spring, thus making the movement such as to minimize the tendency to

65 damage cigarettes by reason of this dis-

charging action. As shown in Figs. 5 and 8, this places the cigarettes in charge from below the dial and plate 58 ready for the beginning of the packaging operation.

This particular form of mechanism is 70 especially adapted for forming charges of cigarettes or other articles such as pencils, crayons, etc. Where the charge is of solid material, as for instance a plug of tobacco, this mechanism may be greatly simplified 75 by omitting the partitions of the pockets and dispensing or simplifying the discharging mechanisms shown in Figs. 7 and 8, it being possible to discharge a solid charge on to a supporting member located in the plane 80 of plate 64 in Fig. 8 either by gravity or by the use of a simple plunger; obviously, an ordinary magazine could be employed in place of the particular hopper structure shown in the drawings. 85

With the supporting plate 64 in the position shown in Fig. 8 and with the charge on such plate, the charge is positioned in the path of travel of a reciprocating plunger 73 which is adapted to advance the charge, 90 indicated generally at A, into contact with a wrapper blank W supported in a vertically extending chute 74, the advance of the charge withdrawing the wrapper blank from said chute and carrying it into a 95 folding channel 75, said channel having upper and lower walls adapted to fold the wrapper into contact with the top and bottom faces of the charge. The channel also carries side plates 75^a which act to turn in 100 end portions to produce a partially wrapped packet approximately as shown in Fig. 18.

At the outer end of channel 75 is mounted a vertically reciprocating carrier 76 also having a channel and side plates 76^a, this 105 carrier being adapted to receive the partially wrapped charge as it emerges from channel 75, carrier 76 being at its upper extreme of movement at this time. The movement of plunger 73 is such that while 110 the charge and that portion of the wrapper in advance of the rear plane of the charge is positioned within the channel of carrier 76, the rearwardly projecting portion of the wrapper remains within channel 75 until 115 withdrawn therefrom by the downward movement of carrier 76, this downward movement acting to fold the rearwardly projecting portion of the wrapper against the rear face of the charge, as shown in Fig. 19. 120 The movement of carrier 76 downwardly to the opposite extreme of its movement brings the charge opposite the entrance to a folding channel 77 and in the path of travel of a reciprocating plunger 78 which operates 125 on a plane parallel to and below that of the plane of plunger 73.

While the channel of carrier 76 is provided with upper and lower faces and with side plates similar to channel 75, no addi- 130

tional folding action is provided by such arrangement, the purpose being to maintain the folds previously made as well as to maintain the cigarettes in proper charge formation while being transferred from the upper to the lower planes.

- The direction of advance movement of plunger 78 is opposite that of the advance movement of plunger 73, so that when the 10 charge is brought to the lower plane and into the path of movement of plunger 78, the end of the wrapped charge which was in advance during travel of the charge through channel 75 becomes the rear end of the charge 15 when the carrier has been shifted. Hence, when the advance movement of plunger 78 takes place, the folding of the packet having progressed to the position shown in Fig. 19, the initial movement of the packet into 20 channel 77 causes the upwardly extending wall of the wrapper to be turned on to the outer face of the charge, as in Fig. 20. As channel 77 carries side plates for folding in the ends, and grooves for successively fold- 25 ing the upper and lower flaps as the package is advanced, the advance movement of the packet under the action of plunger 78 produces the successive operations shown in Figs. 21 to 23, thus completing the wrapping 30 of the charge and placing the wrapped charge opposite the entrance to a channel 108 extending horizontally at right angles to channel 77. The folding plates and grooves of channel 77 are of usual arrangement and are not specifically described.

Plungers 73 and 78 may, of course, be operated in any suitable manner. However, I prefer, to provide proper timing action, to operate these plungers (together with an 40 additional plunger presently referred to) from a single mechanism which, in the present instance, is in the form of a cam 80, shown diagrammatically in detail in Fig. 13, this figure indicating a cam groove ar- 45 rangement which produces alternate periods of activity and dwell in the movement of a reciprocating arm 81 carrying a roll 81^a operative in the cam groove, the arm being connected to a crank 82 mounted on a shaft 50 83, said shaft carrying an arm 84 which is operatively connected to a pivoted lever 85 the upper end of which is connected to plunger 78 by means of a link 86.

Cam 80 is mounted on shaft 87 extending 55 at right angles to shaft 51, these shafts being operatively connected by bevel gears 88, this arrangement causing continuous rotation of cam 80, the cam groove causing arm 81 to rock shaft 83, which movement, 60 through the slide connection between lever 85 and arm 84 oscillates lever 85 and produces the reciprocating movement of plunger 78, the latter, together with plunger 73, being mounted in suitable guides. Plunger 73, is operated from lever 85 through

link connections 89, pivoted lever 85^a and link 86^a, thus causing both plungers 73 and 78 to move at the same time but in opposite directions. As the length of movement of plunger 73 is greater than that of plunger 78, link connection 89 is so arranged as to provide the proper throw of the two levers 85 and 85^a, the latter obviously traveling at a greater speed than lever 85.

As shown in Fig. 5, plunger 78, in advancing the packet through channel 77, extends through the channel of carrier 76, remaining in such channel until the plunger is again withdrawn, this latter action, due to the positive connection between levers 85 and 85^a, taking place concurrently with the advance of plunger 73. However, the parts are so arranged that plunger 78 passes out of carrier 76 before plunger 73 has advanced the packet to the outer end of channel 75, 85 a sufficient length of time elapsing to permit carrier 76 to move to its upper position where it will receive the advancing packet. The movements of carrier 76 are provided by a cam 90 mounted on shaft 87, a vertically extending member 91, slideable in bearing 91^a, supporting the carrier and being operated by cam 90.

Any suitable form of wrapper supply may be employed for feeding and positioning the 95 wrapper in chute 74. For instance, the wrappers may be previously cut and fed to position by suitable feeding mechanism. However, I prefer to supply the wrappers from a web having a width equal to the 100 width of the wrapper, the web being cut into proper lengths by operating mechanism on the machine. One form of mechanism for producing this result will now be described.

92 indicates a pair of rolls mounted at a 105 suitable point above chute 74, these rolls acting to feed the web from a web supply indicated as in the form of a roll 93 removably mounted in brackets 94, the web passing between rolls 92 and downwardly into chute 110 74, a stop 74^a limiting the downward travel of the web. The web feeding action is had by driving one of the rolls 92 positively, and as the wrapper blank, when positioned in chute 74, extends across the path of travel 115 of plunger 73, this feed movement of the web must take place at such time when the plunger 73 is in its rear position; hence the mechanism for driving the rolls 92 operates intermittently, this intermittent movement 120 also tending to prevent more or less buckling of the web when being fed into contact with stop 74^a.

As shown in Figs. 4 and 5, the shaft of the driven roll 92 carries a sprocket wheel 95 operatively connected with a sprocket wheel 96 on a shaft 97, said latter shaft carrying a mutilated gear 98 which cooperates with a complementary gear 99 mounted on shaft 100. Shaft 100 is geared to a ver- 130

tical shaft 101, said latter shaft having a gear connection with a shaft 102 having a gear connection with shaft 51, these latter gear connections being of suitable type, as 5 for instance spiral gears.

By this arrangement, mutilated gear 99 will be driven constantly from shaft 51 through the drive connections indicated. Owing, however, to the form of gears 98 10 and 99, gear 98 will be given one revolution during a portion of the revolution of gear 99, gear 98 remaining stationary during the remainder of the revolution of gear 99. The gear relation is so arranged that feeding of 15 the web will take place while plunger 73 is in rear of the plane of chute 74, and the feed movement will be sufficient to carry the required amount of web into the chute.

To sever the web to form the individual 20 wrapper, I employ a cutting mechanism in the form of a stationary knife blade 103 and a movable knife blade 104, the latter being movable across the path of travel of the web. Knife blade 104 is reciprocated inter- 25 mittently by means of a cam 105 mounted on shaft 57^b, the configuration of this cam being shown more particularly in Fig. 1. Cam 105 is adapted to operate an arm 106 to which the support for blade 104 is at- 30 tached, the arm carrying a roller adapted to contact with the edge of the cam. As shown more particularly in Fig. 1, arm 106 straddles shaft 57^b, forming a guide to limit the the movement of the arm to a single plane, 35 the arm roller being held in contact with the cam by suitable springs 106^a mounted between a stationary member 107 and the heads of pins 106^b connected to the arm; the advance movement of the arm under the action 40 of the cam being against and increasing the tension of springs 106^a, the latter retracting the arm when the configuration of the cam permits. Since cam 105 operates intermittently, moving with dial 75, it will be under- 45 stood that an accurately timed cutting operation may be provided. Obviously, advance of blade 104 will sever the web, thus producing a wrapping blank of proper length, the blank being supported in a vertical plane 50 within the chute and properly registered with the travel path of the charge by reason of contact of the lower end of the wrapper with stop 74^a. The cutting operation takes place while the web is stationary, and the 55 succeeding feed of the web takes place only after the severed wrapper has been carried out of the chute and plunger 73 has returned.

As heretofore indicated, completion of the 60 advance movement of plunger 78 places the wrapped charge in alinement with the entrance of a third channel which extends at right angles to channel 75. This channel is indicated at 108. The wrapped package is 65 advanced in this channel by a third plunger

109 which has its path of travel in a direction at right angles to the direction of travel of plungers 73 and 78, the path of movements of plungers 78 and 109 being on the same horizontal plane, the extreme of advance movement of plunger 78, however, being insufficient to cause it to intersect the path of travel of plunger 109.

The movements of plunger 109 may be provided in any desired manner, but I prefer to operatively connect this plunger to the mechanism for operating plungers 73 and 78, thus placing the control of the movements of these plungers on a single element, viz: cam 80. One way of obtaining this result is by operatively connecting shaft 83 to a shaft 110 by bevel gears, shaft 110 carrying an arm 111 having a slidable connection with a lever 85^b connected with plunger 109 by link 86^b, the gear ratio being arranged to 80 provide the desired length of movement of plunger 109 during the oscillating movements of shaft 83.

By this arrangement of operating mechanisms, plungers 73 and 109 have their advance movements concurrently and during the period when plunger 78 is moving rearwardly, the advance movement of plunger 78 taking place when plungers 73 and 109 are returning to their outer positions. Consequently, at the time when plunger 73 begins this advance movement with the new charge, plunger 109 begins its advance movement on the previous charge which has been wrapped in passing through channels 75 95 and 77, the result being that the capacity of the machine is controlled practically by the length of time required to initially wrap the charge, packaging operations taking place during the wrapping of the succeeding 100 charge.

As will be understood, the wrapping operation has been provided in such manner that when the wrapped charge is presented to channel 108, one of the ends of the packet 110 will be presented as the advance end, the wrapper at such end having the folded end flap shown in Fig. 23, plunger 109 operating in rear of the opposite end flaps. Advance of plunger 109 carries this advance end of 115 the packet into contact with a stamp positioned in a chute 112 with a portion of the stamp exposed to the advancing packet. The stamp, indicated at S, is fed into position by suitable means, the stamp being 120 preferably positioned in such manner as to produce the approximate relationship between the stamp and the wrapped packet shown in Fig. 24, the stamp having its rear face more or less "tacky" at the time when 125 contact is made so that the stamp will adhere to the packet. As the packet advances after such contact, it is carried between upper and lower faces of channel 108, this advance movement withdrawing the stamp from the 130

chute and at the same time folding the upper end of the stamp on to the top of the packet in overlying relation to the joint formed by the opposite ends of the wrapper 5 at the top of the packet, the lower projecting portion of the stamp being drawn over the under face of the packet, the excess length of the stamp trailing beyond the rear of the packet.

10 Further advance of the plunger brings the advance end of the packet—with the stamp superposed thereupon—into contact with a container blank C positioned in a chute 113, the advance end of the packet contacting 15 with that portion of blank C which forms the bottom of the completed container, as shown in Fig. 25, which figure also discloses a preferred configuration of blank C. Blanks C are positioned in the chute by suitable mechanism, the mechanisms for feeding the blank and the stamp being adapted to deliver them subsequent to the withdrawal of plunger 109 and before the succeeding advance movement of the plunger, the feed 20 mechanisms being operatively connected to moving parts of the apparatus to provide the proper timed operation.

As plunger 109 continues its advance travel, blank C is withdrawn from its chute, 30 passing between upper and lower face of channel 108 which fold opposite sides of the blank on to the packet, this being followed by bringing the uppermost side flaps into contact with a pair of adhesive-applying 35 rolls 114 which act to place a stripe of adhesive on the upper face of these flaps and at the same time inturn the flaps to a more or less extent, such for instance, as shown in Figs. 10 and 26, the inturning of these flaps 40 bringing the striped faces outermost. Further advance of plunger 109 then brings the advancing partially-packaged packet into contact with a pair of rolls 115 which act to turn up the lower flaps, the inner faces of 45 which contact with the striped faces of the upper flaps, thus adhesively connecting the opposite flaps together and bringing the package into the form shown in Fig. 27, the container being partially formed, the end 50 laps, the closing flap, and the stamp projecting in rear of the wrapped packet which is now partially enveloped by the container. The package, in this form is advanced until positioned over a well 116, this positioning 55 action completing the work to be performed by plunger 109, said plunger being in the extreme of its advance movement when the package is thus positioned. At this time, the end laps and closing flap of the container and 60 the trailing portion of the stamp, still remain in channel 108.

After plunger 109 begins its withdrawal movement, leaving the package in position over the well, a pair of fingers 117 are rendered operative to turn in the end laps,

placing the package in the form shown in Fig. 28. This inturning action is provided by the movements of a pair of bell crank levers 117^a which are operatively connected to fingers 117, said levers 117^a being connected to a pivoted lever 118 by link connection 118^a, the movements of lever 118 being controlled by a cam 119 mounted on a vertical shaft 120 geared to shaft 102.

After the end laps have been turned in, 75 the package is moved downwardly within the well a distance equal to the thickness of the package, this movement causing the closing flap of the container and the trailing portion of the stamp to be turned up 80 against the end of the package, producing an arrangement such as shown in Fig. 29, a portion of the closing flap and the stamp projecting above the top plane of the container which, at this time, is located substantially on a plane corresponding to the bottom plane of the succeeding package, the advance of which to its position over the well, folds the portions of the stamp and closing flap previously projecting above the 90 top plane of the container on to the upper face of the container, thus bringing the projecting portion of the stamp into a position to be adhesively connected to the container face, and the closing flap in overlying relation to the stamp and such face, the pressure on the upper face as the container travels through the well, causing this adhesive connection to be provided.

The initial downward movement of the 100 container into the well is provided by a plunger 121 carried by an arm 122 mounted on a vertically reciprocating member 123, the latter being operatively connected to a pivoted lever 124 the movements of which 105 are controlled by a cam 125 mounted on shaft 51.

The well is of suitable construction, one form being provided by the use of endless bands 126 to form two opposing walls of 110 the well, the remaining walls being provided by plates. The bands are preferably of the spring coil type under more or less tension, such structure tending to maintain the wall configuration and at the same time 115 provide a structure which will prevent free downward travel of the packages within the well, it being preferred that the downward movement of the packages be provided entirely by the movement of plunger 120 121, thus not only providing pressure tending to produce the adhesive connection of stamp and container, but also to position one container in such manner as to properly register the projecting closing flap and 125 stamp with the succeeding advancing package.

Any suitable adhesive-applying mechanism may be employed, that shown being in the form of a container 114^a forming the 130

adhesive supply, rolls 114 extending into this supply. If desired, rolls 114 may be operatively connected to shaft 120 to permit of roller movement to properly apply 5 the adhesive and inturn the flaps.

As heretofore pointed out, any suitable feed mechanisms for the stamp and for the container blank may be employed. For 10 purposes of illustration, however, I have shown, more or less diagrammatic, preferred forms of mechanism for this purpose, these mechanisms being more particularly shown and described in companion applications. The mechanisms for feeding the 15 stamp and the container blank differ in some respects from each other, due somewhat to the character of the materials fed and the specific requirements. For instance, the stamp is of comparatively thin flexible paper and is to be adhesively connected to the wrapped packet. Since the stamp may be either of a form carrying the adhesive which must be moistened prior to application of the packet, or receive an adhesive coating or 20 striping while passing to its applying position, means must be provided for producing the more or less "tacky" face to the stamp prior to entry into its receiving chute. On the contrary, the container blank is of heavier weight and requires no preliminary application of adhesive. In either mechanism, however, it is desirable that the stamp or container blank, as the case may be, be positioned vertically and be unfolded and 25 free from material bending. In addition, the particular formation of the container blank is such that a slightly different manipulation should be had in order to insure for proper feed.

40 In Fig. 14 I have shown a mechanism which is adapted to provide the stamp feeding operation, this view showing a supporting table 127 for a pile of stamps, with a reciprocating feeding element 128 mounted 45 to operate practically in the top plane of the table, this element having a pair of rolls 129 carrying endless bands, the rolls being supported on a carriage 130, the carriage being movable in suitable guides by means of a link 131 carried by a crank wheel 132 mounted on a shaft 133. Shaft 133 may be operatively connected to vertical shaft 101 by bevel gears, thus providing for rotation of shaft 133. Rolls 129 are free to rotate in one 50 direction and held against rotation in the opposite direction by suitable means such as a pawl and ratchet, the parts being so arranged that the rolls and the upper flight of the bands are in contact with the lowermost stamp, and during the advancing movement of the carriage, the rolls are held against rotation, the result being that the rolls and band or bands frictionally engage the lowermost stamp and advance it; during 55 the return movement of the carriage, the

rolls will rotate so that no frictional engagement with the stamp is provided, permitting the carriage to return to its rear position and again advance to feed the next stamp. Since it is preferable that the stamps lie 70 in a horizontal plane when in pile form and the stamp be delivered into chute 112 in a vertical direction, I have provided a transfer structure which changes the direction of travel of the stamp from horizontal to vertical, this structure being in the form of a pair of rolls 134 to which the stamp is delivered by the advancing carriage and which rolls in turn deliver the stamp to a vertical band-formed flight which carries the stamp 80 past an adhesive-applying device 135, the stamp being delivered into chute 112 with its rear face coated. In order to avoid confusion, I have omitted, in Fig. 1, this stamp feeding mechanism, but I have indicated this 85 position by dotted outlines indicated at SF, it being readily understood that this feeding mechanism may be supported on brackets carried by the frame at a suitable point above the plane of the folding channels. 90

The feeding mechanism for the container blank omits the vertical band-formed flight, rolls 134 receiving the blank and delivering the blank to the upper end of chute 113 which is preferably provided with a curved 95 face adapted to shift the direction of travel of the blank to the vertical, rolls 134 thus delivering the blank directly to the chute instead of indirectly as in the stamp feeding mechanism. 100

Due to the large size of the container blank and the presence of cut-away portions in the length of the blank, I preferably vary the mechanism to meet these conditions, Figs. 15 and 16 showing a simple form of 105 mechanism which may be employed as an auxiliary to the carriage of the stamp mechanism, it being understood, of course, that the width of the blank-engaging portions of the carriage will preferably be increased 110 over the width employed in connection with the stamp feed. In this particular form, I preferably arrange the pile of blanks sufficiently to one side of the path of travel of the blank being fed in order that the projecting flaps of the lower blank will be out of vertical alinement with the flaps of the blank above it, so that there is practically no liability of the feed of the blank being obstructed by a flap of the lower blank being 115 caught by the flap of the superposed blank. Therefore, to properly feed the blank, the lowermost blank must be shifted laterally of the pile into proper position above the frictional surfaces of the carriage. This action 120 is produced by a slideable plate 136 positioned on the table to move in a direction at right angles to the direction of travel of the carriage, this plate having a sufficient projection above the table surface so as to move 125 130

the lowermost blank of the pile when the plate is advanced toward the friction faces of the carriage. As will be obvious, this laterally-advancing movement of the blank 5 takes place while the carriage is moving rearwardly or is in its rear position in order that the blank may be in proper position when the carriage begins its advance movement to advance the blank to rolls 134. To 10 produce this result I operatively connect slide plate 136 to the carriage through suitable link connections, indicated at 137, the rearward movement of the carriage causing the link connections to advance plate 136 15 at the proper time, the forward movement of the carriage withdrawing the plate to a position where it will engage the succeeding blank when the plate is again advanced.

For reasons above pointed out, I have 20 omitted the specific structure of the blank feeding mechanism in Fig. 1, but have indicated its position by the dotted line representation BF. Shaft 133 of the blank mechanism may be operatively connected to vertical shaft 120, the feeding mechanism being 25 supported by suitable brackets above channel 108.

As heretofore pointed out, the embodiment of the invention shown is designed 30 more particularly for the packaging of cigarettes or other articles into package form, these articles being first arranged in the form of charges and then subjected to the wrapping and succeeding operations. Obviously, 35 the mechanisms may be readily arranged to provide a similar result where the commodity is more or less solid, as for instance plug tobacco, a commodity in which the several articles are substantially equal in 40 size and hence are adapted to be individually wrapped in the manner herein disclosed.

Obviously, the charge-forming mechanism may be of any preferred type, that shown in the drawings being a simple way in which 45 to produce a charge of this particular character without subjecting the individual cigarettes to an action which would tend to damage them. It will, of course, be understood that so far as the actual packaging of the 50 charge is concerned, the charge might be preformed and held in charge form in any suitable manner and delivered into the space in advance of plunger 73. This space may be considered as the receiving station for the 55 charge or commodity to be wrapped, while the structure at the inner end of channel 77 into or on which the wrapped charge or commodity is delivered by the movement of plunger 78, may be considered as the delivery 60 station for the wrapped charge or commodity—the wrapped packet.

It is also to be understood that although 65 the several mechanisms herein described operate in a predetermined sequence with a more or less timing relationship, it will be

understood that this complete combination may be varied. For instance, the packaging of the wrapped charge is dependent upon the supplying of the stamps and the container blanks in the path of travel of the 70 packet. If the supply of either be omitted, the apparatus will operate to deliver the wrapped packet in its wrapped form or with a stamp thereon, or with the container positioned thereon without stamp, depending 75 on which element is omitted. Obviously, therefore, one or more of the mechanisms may be entirely omitted to meet the exigencies of a desired use in so far as such omission may be permitted by the scope of 80 the accompanying claims when broadly construed. And obviously, the individual mechanisms may be varied to meet the individual needs of the packaging operation without departing from the spirit and scope of the 85 invention in so far as permitted by such claims.

The invention is not limited to the complete formation of packages of the particular type indicated. For instance, the mechanism employed in wrapping the charge may be employed in connection with other forms of mechanism for producing a different type of package, the advance movement of plunger 78 placing the wrapped package in a 95 position where it may be acted upon by other mechanisms for completing the packaging operation in a different manner.

While I have described the mechanism as adapted to apply a revenue stamp, it will 100 be obvious that a strip or label may be applied in place of the stamp where the package is of a form not requiring such stamp, and the term "stamp" is intended as synonymous with and including such 105 strip or label structures.

Having thus described my invention, what I claim as new, is:—

1. In packaging machines, wrapping mechanism having charge-receiving and wrapped-packet delivery stations and operative to wrap the article or charge while advancing from the charge-receiving to the packet delivery station, means for advancing the packet from said latter station in a pre-determined path, means for positioning a stamp and a container blank at successive points in such path, and means for applying the stamp to the packet and for folding the container blank to inclose the packet and its applied stamp during travel in such path.

2. In packaging machines, wrapping mechanism having charge-receiving and wrapped-packet delivery stations and operative to wrap the article or charge while advancing from the charge-receiving to the packet delivery station, means for advancing the packet from said latter station in a pre-determined path, means for positioning a stamp and a container blank at successive 130

points in such path, means for applying the stamp to the packet with a projecting stamp end and for folding the container blank to inclose the packet and its applied stamp during travel in such path, and means for applying the projecting stamp end to an exterior face of the container.

3. In packaging machines, wrapping mechanism having charge-receiving and wrapped-
5 packet delivery stations and operative to wrap an article or charge while advancing from the charge-receiving to the packet delivery station, means for positioning the article or charge in the charge-receiving station, means for advancing the wrapped packet from the packet delivery station in a predetermined path, means for supporting a stamp and a container blank in such path, and means for inclosing the packet within 10 the container with the stamp applied to the packet and container during packet travel in such path.

4. In packaging machines, wrapping mechanism having charge-receiving and wrapped-
15 packet delivery stations positioned in parallel planes, said mechanism also having wrapping channels in both planes, means for advancing the charge and wrapper blank through such channels to completely wrap 20 and deliver the wrapped packet in the packet delivery station, means for advancing the packet from said latter station in a predetermined path, and means for inclosing the packet in a container and for applying 25 a stamp to the packet and container during travel in such path.

5. In packaging machines, wrapping mechanism having charge-receiving and wrapped-
30 packet delivery stations positioned in parallel planes, said mechanism also having wrapping channels in both planes, means for advancing the charge and wrapper blank through such channels to completely wrap 35 and deliver the wrapped packet in the packet delivery station, means for advancing the packet from said latter station in a predetermined path, and means for inclosing the packet in a container and for applying 40 a stamp to the packet and container during travel in such path; said stations and wrapping channels being relatively positioned to permit advance of one charge from the charge-receiving station concurrently with movements of the preceding wrapped 45 packet in its container inclosing path.

6. In a wrapping machine, means for conveying an assembled charge and wrapper along a predetermined path, and stationary elements adjacent said path for folding the 50 wrapper about four consecutive faces of the charge, folding projecting marginal wrapper portions against the remaining charge faces to produce wing flaps, and folding said 55 wing flaps flatwise against said remaining faces of the charge.

7. In a wrapping machine, a plurality of channels, means for conveying an assembled charge and wrapper through the first channel, means for conveying the assembly from the first channel to the second channel, 70 means for conveying the assembly through the second channel, and means forming a part of said channels operative on the assembly between the entrance to the first channel and the exit from the second channel 75 for folding the wrapper flatwise against all the faces of the package.

8. In a wrapping machine, a plurality of channels, means for conveying an assembled charge and wrapper through the first channel, 80 means for conveying the assembly from the first channel to the second channel, means for conveying the assembly through the second channel, and stationary means operative on the assembly between the entrance to the first channel and the exit from the second channel for folding the wrapper flatwise against all the faces of the charge.

9. In a wrapping machine, a plurality of parallel channels, means for conveying an assembled charge and wrapper through the first channel, means for conveying the assembly from the first channel to the second channel, 90 means for conveying the assembly through the second channel, and means operative on the assembly between the entrance to the first channel and the exit from the second channel for folding the wrapper flatwise against all the faces of the package.

10. In a wrapping machine, a plurality of parallel superposed channels, means for conveying an assembled charge and wrapper through the first channel, means for conveying the assembly from the first channel to the second channel, 100 means for conveying the assembly through the second channel, and means operative on the assembly between the entrance to the first channel and the exit from the second channel for folding the wrapper flatwise against all the faces of the package.

105

11. In a wrapping machine, a plurality of parallel channels, means for conveying an assembled charge and wrapper through the first channel in one direction, means for conveying the assembly from the first channel to the second channel, means for conveying the assembly in the opposite direction through the second channel, and means operative on the assembly between the entrance 115 to the first channel and the exit from the second channel for folding the wrapper flatwise against all the faces of the package.

12. In a wrapping machine, a plurality of parallel channels, plunger means for conveying an assembled package and wrapper through the first channel in one direction, means for conveying the assembly from the first channel to the second channel, plunger means for conveying the assembly in the op- 125 130

posite direction through the second channel, and means operative on the assembly between the entrance to the first channel and the exit from the second channel for folding 5 the wrapper flatwise against all the faces of the package.

13. In a wrapping machine, a plurality of channels, means for conveying an assembled charge and wrapper through the first channel, a reciprocated carrier adapted to receive the assembly from the first channel and shift it into operative relation to the second channel, and means for conveying the assembly through the second channel 15 and means operative on the assembly between the entrance to the first channel and the exit from the second channel for folding the wrapper flatwise against all faces of the charge.

20 14. In machines for wrapping packages, a receiving station for the charge to be wrapped and from which the charge is advanced, a wrapper blank station, a delivery station for the wrapped packet, wrapping mechanism intermediate the wrapper blank station and the packet delivery station, and means for successively advancing the charge into contact with the wrapper blank and through the wrapping mechanism; said 25 wrapping mechanism including a pair of folding channels for combinedly folding the wrapper to provide overlapping wrapper ends on one face of the packet, infolding of the end flaps of said wrapper ends being 30 provided in one of said channels.

40 15. In machines for wrapping packages, a receiving station for the charge to be wrapped and from which the charge is advanced, a wrapper blank station, a delivery station for the wrapped packet, wrapping mechanism intermediate the wrapper blank station and the packet delivery station, and means for successively advancing the 45 charge into contact with the wrapper blank and through the wrapping mechanism, said means including a pair of reciprocating plungers operatively connected to move in unison, a rotatable shaft, and mechanism operatively connecting said shaft and one 50 of said plungers for reciprocating the latter.

55 16. In machines for wrapping packages, a receiving station for the charge to be wrapped and from which the charge is advanced, a wrapper blank station, a delivery station for the wrapped packet, wrapping mechanism intermediate the wrapper blank station and the packet delivery station, and means for successively advancing the 60 charge into contact with the wrapper blank and through the wrapping mechanism, said means including a pair of reciprocating plungers operatively connected to move in unison, a rotatable shaft, and mechanism 65 operatively connecting said shaft and one of

said plungers for reciprocating the latter, said latter mechanism including a cam on said shaft, a rock shaft, operative connections between the cam and rock shaft to oscillate the latter, and operative connections 70 between the rock shaft and the plunger.

17. In machines for wrapping packages, a receiving station for the charge to be wrapped and from which the charge is advanced, a wrapper blank station, a delivery 75 station for the wrapped packet, wrapping mechanism intermediate the wrapper blank station and the packet delivery station, and means for successively advancing the charge into contact with the wrapper blank and 80 through the wrapping mechanism, said means including a pair of reciprocating plungers movable in unison and having their advancing movements in opposite directions, mechanism for operating one of said 85 plungers, and operative connections between said plungers to cause movements of the other plunger, said connections causing one plunger to have a length of reciprocation less than that of the other plunger. 90

18. In machines for wrapping packages, a receiving station for the charge to be wrapped and from which the charge is advanced, a wrapper blank station, a delivery 95 station for the wrapped packet, wrapping mechanism intermediate the wrapper blank station and the packet delivery station, and means for successively advancing the charge into contact with the wrapper blank and through the wrapping mechanism, said 100 wrapping mechanism including a pair of channels extending in substantially parallel planes and being operative successively to fold wrapper portions over the top, bottom and end faces of the packet and folders 105 located at the sides of the channels for folding other wrapper portions over the side faces of the packet.

19. In machines for wrapping packages, a receiving station for the charge to be wrapped and from which the charge is advanced, a wrapper blank station, a delivery station for the wrapped packet, wrapping mechanism intermediate the wrapper blank station and the packet delivery station, and means for successively advancing the charge into contact with the wrapper blank and through the wrapping mechanism, said 110 wrapping mechanism including a pair of channels extending in substantially parallel planes and being operative successively to fold wrapper portions over the top, bottom and end faces of the packet and folders located at the sides of the channels for folding other wrapper portions over the side faces 115 of the packet, and means for shifting the packet from the plane of one channel to that of the other, said advancing means being operative from opposite sides of the shifting means. 125

20. In machines for wrapping packages, a receiving station for the charge to be wrapped and from which the charge is advanced, a wrapper blank station, a delivery station for the wrapped packet, wrapping mechanism intermediate the wrapper blank station and the packet delivery station, and means for successively advancing the charge into contact with the wrapper blank and through the wrapping mechanism, said wrapping mechanism including a pair of channels extending in substantially parallel planes and being operative successively to fold wrapper portions over the top, bottom and end faces of the packet and folders located at the sides of the channels for folding other wrapper portions over the side faces of the packet, and transfer mechanism operative to shift the partially wrapped packet from the plane of one channel to that of the other, said advancing means including plungers located on opposite sides of the transfer mechanism and operative in the respective channels.
21. In machines for wrapping packages, a receiving station for the charge to be wrapped and from which the charge is advanced, a wrapper blank station, a delivery station for the wrapped packet, wrapping mechanism intermediate the wrapper blank station and the packet delivery station, and means for successively advancing the charge into contact with the wrapper blank and through the wrapping mechanism, said wrapping mechanism including a pair of channels extending in substantially parallel planes with the direction of packet advance through one channel opposite that of the other channel, and being operative successively to fold wrapper portions over the top, bottom and end faces of the packet and folders located at the sides of the channels for folding other wrapper portions over the side faces of the packet, and transfer mechanism for receiving the partially wrapped packet from one channel and positioning it in the plane of the other channel.
22. In packaging machines, wrapping mechanism including a pair of wrapping channels extending in substantially parallel planes, plungers operative in said channels for advancing the wrapper and its contents through the wrapping mechanism and for positioning the wrapped packet at a packet delivery station, the construction of the channels being such that the channels are operative to fold the wrapper over the top, bottom and end faces of the contents during movement of the same with respect to the channels, a channel extending transverse to the direction of length of the wrapping channels and in the plane of said station, and a plunger adapted to move the packet through said latter channel.
23. In packaging machines, wrapping mechanism including a pair of wrapping channels extending in substantially parallel planes, plungers operative in said channels for advancing the wrapper and its contents through the wrapping mechanism and for positioning the wrapped packet at a packet delivery station, a channel extending transverse to the direction of length of the wrapping channels and in the plane of said station, and a plunger adapted to move the packet through said latter channel, a driven element, and operative connections between said driven element and said plungers to cause them to move in unison.
24. In packaging machines, wrapping mechanism including a pair of wrapping channels extending in substantially parallel planes, plungers operative in said channels for advancing the wrapper and its contents through the wrapping mechanism and for positioning the wrapped packet at a packet delivery station, said plungers being operatively connected together, a channel extending transverse to the direction of length of the wrapping channels and in the plane of said station, a plunger adapted to move the packet through said latter channel, a driving element, means for operatively connecting one of the wrapping plungers to the driving element, and connections between the transversely operating plunger and said latter means for moving said latter plunger in synchronism with the wrapping plungers.
25. In packaging machines, wrapping mechanism including a pair of wrapping channels extending in substantially parallel planes, a plunger for each of said channels, said plungers being operatively connected together and having their advancing movements in opposite directions, one of said channels completing the wrapping operation by the advancing movement of its plungers, said plunger positioning the wrapped packet at a packet delivery station, a channel extending transverse to the direction of length of the wrapping channels and in the plane of the packet delivery station, a plunger for said latter channel, and means for concurrently operating said plungers, said means including connections whereby the transverse channel plunger will advance during the retreating movement of the packet delivery plunger.
26. In packaging machines, wrapping mechanism including a wrapping channel for completing the wrapping of the packet and having a packet delivery station at its discharge end, a channel extending transverse to the direction of length of the wrapping channel and in the plane of said station, an element for positioning a stamp to intersect said channel and in the path of an advancing packet, and means for moving the wrapped packet from said station into con-

- tact with the stamp and for advancing the packet and stamp to apply the stamp to opposite faces of the packet.
27. In packaging machines, wrapping mechanism including a pair of wrapping channels extending in substantially parallel planes, one of said channels completing the wrapping operation to produce the wrapped packet, a packet delivery station at the discharge end of said latter channel, a channel extending transverse to the direction of length of the wrapping channels and in the plane of said station, an element for positioning a stamp to intersect said transverse channel, and means for moving the wrapped packet from said station into contact with the stamp and for advancing the packet and stamp to apply the stamp to opposite faces of the packet.
28. In packaging machines, wrapping mechanism including a stationary wrapping channel for completing the wrapping operation and having a packet delivery station at its discharge end, a channel extending transverse to the direction of length of said wrapping channel and in the plane of said station, means for advancing the wrapped packet through said channel, an element for positioning a stamp to intersect said channel and in the path of movement of an advancing packet, and stamp feeding mechanism operative to deliver a stamp to said element while said channel is unobstructed at the point of stamp intersection.
29. In packaging machines, wrapping mechanism including a wrapping channel formation adapted to wrap the charge with folded end flaps and with wrapper ends positioned on a face of the packet, a packet delivery station at the discharge end of such channel formation, a channel extending transverse to the direction of length of said channel formation and in the plane of such station, the packet, when in the packet delivery station, having a flap folded end facing the entrance to said latter channel, means for positioning a stamp to intersect said latter channel, and means for advancing the packet into and through said channel to apply stamp portions to said packet by the advance movement of the latter, said stamp being positioned in a manner to overlie portions of the wrapper meeting edges and the advance folded flap ends of the packet.
30. In packaging machines, wrapping mechanism for completely applying a wrapper to form a wrapped packet, said mechanism including a stationary wrapping channel terminating in a stationary delivery station for the wrapped packet, and means for positioning the packet within a container, said means including a channel extending from and in the plane of said station, means for supporting a container blank to intersect said channel, a plunger operative to advance the packet into and through said channel, whereby said packet will be brought into registration contact with said blank and the blank will be advanced by and with said packet, and container folding mechanism in the path of travel of the packet and blank.
31. In packaging machines, wrapping mechanism for completely applying a wrapper to form a wrapped packet, said mechanism including a stationary wrapping channel terminating in a stationary delivery station for the wrapped packet, and means for positioning the packet within a container, said means including a channel extending from and in the plane of said station, means for supporting a container blank to intersect said channel, a plunger operative to advance the packet into and through said channel, whereby said packet will be brought into registration contact with said blank and the blank will be advanced by and with said packet, container folding mechanism in the path of travel of the packet and blank, and means for applying adhesive to predetermined portions of the container blank during its travel through said channel.
32. In packaging machines, wrapping mechanism for completely applying a wrapper to form a wrapped packet, said mechanism including a stationary wrapping channel terminating in a stationary delivery station for the wrapped packet, and means for positioning the packet within a container, said means including a channel extending from and in the plane of said station, means for supporting a container blank to intersect said channel, a plunger operative to advance the packet into and through said channel, whereby said packet will be brought into registration contact with said blank and the blank will be advanced by and with said packet, and container folding mechanism in the path of travel of the packet and blank, said folding mechanism including adhesive applying mechanism operative within said channel and on predetermined side flaps of the blank, and means for folding complementary side flaps to provide adhesive connection thereof.
33. In packaging machines, wrapping mechanism for completely applying a wrapper to form a wrapped packet, said mechanism including a stationary wrapping channel terminating in a stationary delivery station for the wrapped packet, and means for positioning the packet within a container, said means including a channel extending from and in the plane of said station, means for supporting a container blank to intersect said channel, a plunger operative to advance the packet into and through said channel, whereby said packet will be

brought into registration contact with said blank and the blank will be advanced by and with said packet, container folding mechanism in the path of travel of the packet and 5 blank, a vertically extending well at the discharge end of the channel, and means for completing the container formation while the container is within the well.

34. In packaging machines, wrapping 10 mechanism for completely applying a wrapper to form a wrapped packet, said mechanism including a stationary wrapping channel terminating in a stationary delivery station for the wrapped packet, and means for 15 positioning the packet within a container, said means including a channel extending from and in the plane of said station, means for supporting a container blank to intersect said channel, a plunger operative to 20 advance the packet into and through said channel, whereby said packet will be brought into registration contact with said blank and the blank will be advanced by and with 25 said packet, container folding mechanism in the path of travel of the packet and blank, a vertically-extending well at the discharge end of the channel, means for infolding end laps at the entrance to the well, and means for moving the container within the well to 30 complete the container formation.

35. In packaging machines, wrapping mechanism including a stationary wrapping channel for completing the wrapping operation and having a packet delivery station at 35 its discharge end, a channel extending transverse to the direction of length of said wrapping channel and in the plane of said station, means for advancing the wrapped packet through said channel, an element for 40 positioning a container blank to intersect said channel, container folding mechanism in the path of travel of the packet and blank, and blank feeding mechanism operative to deliver a blank to said element while said 45 channel is unobstructed at the point of blank intersection.

36. In packaging machines, wrapping mechanism, a packet delivery station at which the wrapped packet is delivered by 50 said mechanism, a channel into and through which the packet is advanced, means for positioning a stamp and a container blank to intersect said channel at successive points in the length of the channel, whereby the 55 stamp and blank will be placed in superposed relation to the advance end of the packet by packet movements and be advanced in such relation to fold the blank into overlying relation to opposite faces of the 60 packet, said stamp and blank being relatively positioned to provide a projecting end portion of the stamp when the blank is so folded, and means for completing the container formation, said means being active 65 to apply predetermined portions of the

stamp to the packet within the container and other stamp portions to the container.

37. In packaging machines, wrapping mechanism, a packet delivery station at which the wrapped packet is delivered by 70 said mechanism, a channel into and through which the packet is advanced, means for positioning a stamp and a container blank to intersect said channel at successive points in the length of the channel, whereby the stamp and blank will be placed in superposed relation to the advance end of the packet by 75 packet movements, and be advanced in such relation to fold the blank into overlying relation to opposite faces of the packet, said 80 stamp and blank being relatively positioned to provide a projecting end portion of the stamp when the blank is so folded, and means for completing the container formation, said means being active to apply predetermined portions of the stamp to the 85 packet within the container and other stamp portions to an exterior face of the container.

38. In packaging machines, wrapping 90 mechanism, a packet delivery station at which the wrapped packet is delivered by said mechanism, a channel into and through which the packet is advanced, means for positioning a stamp and a container blank 95 to intersect said channel at successive points in the length of the channel, whereby the stamp and blank will be placed in superposed relation to the advanced end of the packet by packet movements, and means for 100 folding the container into inclosing relation with predetermined portions of the stamp applied to the packet within the container, said means including mechanism for folding and adhesively connecting container side 105 flaps, a well at the discharge end of said channel, and means for positioning the package within the well to affix the stamp and complete the container formation.

39. In packaging machines, wrapping 110 mechanism, a packet delivery station at which the wrapped packet is delivered by said mechanism, a channel into and through which the packet is advanced, means for positioning a stamp and a container blank 115 to intersect said channel at successive points in the length of the channel, whereby the stamp and blank will be placed in superposed relation to the advance end of the packet by packet movements, and means for 120 folding the container into inclosing relation with predetermined portions of the stamp applied to the packet within the container, said means including a well having predetermined walls formed of coil-spring endless 125 bands, and a plunger adapted to move the package into the well, said plunger and band-formed walls coöperating to position the package within the well to complete the package formation.

40. In packaging machines, wrapping mechanism having an article or charge-receiving station, means for positioning successive articles or charges at such station, and article-advancing mechanism movable through said station and in the delivery path of articles or charges to such station, said means including a rotatable dial having charge-receiving compartments, means for 5 moving said dial intermittently, each dial movement positioning a compartment in vertical alinement with such station, means for positioning a charge into a compartment other than that vertically alined with the 10 station, and operating means for connecting the wrapping mechanism and the dial moving means to provide dial movements when said station is obstructed by said mechanism to the entrance of the charge. 15

20 41. In packaging machines, wrapping mechanism having an article or charge receiving station, and means for positioning successive articles or charges at such station, said means including a rotatable 25 dial having charge-receiving compartments, means for moving said dial intermittently, each dial movement positioning a compartment in vertical alinement with such station, means for positioning a charge into a compartment other than that vertically alined with the 30 station, and operating means for connecting the wrapping mechanism and the dial moving means to provide dial movements when said station is obstructed by said mechanism to the entrance of the charge, and means for moving the charge positioned in such compartment vertically into such station. 35

45 42. In packaging machines, wrapping mechanism having an article or charge receiving station, and means for positioning successive articles or charges at such station, said means including a rotatable dial having charge-receiving compartments, means for moving said dial intermittently, each dial 40 movement positioning a compartment in vertical alinement with such station, means for positioning a charge into a compartment other than that vertically alined with the 45 station, and operating means for connecting the wrapping mechanism and the dial moving means to provide dial movements when said station is obstructed to the 50 entrance of the charge, said operating means including a power shaft, means operatively connected to said shaft and movable through said station to move successive charges from said station into the wrapping mechanism 55 at timed intervals, said latter means obstructing the station during such charge-advancing movements. 60

55 43. In packaging machines, wrapping mechanism having an article or charge receiving station, and means for positioning successive articles or charges at such station, said means including a rotatable dial having charge-receiving compartments, means for moving said dial intermittently, each dial 65 movement positioning a compartment in vertical alinement with such station, means for positioning a charge into a compartment other than that vertically alined with the 70 station, and operating means for connecting the wrapping mechanism and the dial moving means to provide dial movements when said station is obstructed by said mechanism to the entrance of the charge, and means for moving the charge positioned in such compartment vertically into such station. 75

80 44. In packaging machines, wrapping mechanism having a wrapper-receiving station and an article or charge receiving station in advance of the wrapper-receiving station, and means for positioning successive charges at such charge-receiving station, said means including a carrier having a charge-receiving compartment positionable above said station, a member movable vertically between a normal position to form a bottom for the compartment and a position to form a charge-supporting bottom for said station, and mechanism for concurrently moving said member from its normal position and for discharging the charge from the compartment. 85

90 45. In packaging machines, wrapping mechanism having a wrapper-receiving station and an article or charge receiving station in advance of the wrapper-receiving station, and means for positioning successive charges at such charge-receiving station, said means including a carrier having a charge-receiving compartment positionable above said station, a member movable vertically between a normal position to form a bottom for the compartment and a position to form a charge-supporting bottom for said station, and mechanism for concurrently moving said member from its normal position and for discharging the charge from the compartment. 95

100 46. In packaging machines, wrapping mechanism having an article or charge receiving station, and means for positioning successive charges at such station, said means including a carrier having a charge-receiving compartment positionable above said station, a member movable vertically between a normal position to form a bottom for the compartment and a position to form a charge-supporting bottom for said station, and mechanism for concurrently moving said member from its normal position and for discharging the charge from the compartment, said member being yieldably supported. 105

110 47. In packaging machines, wrapping mechanism having an article or charge receiving station, and means for positioning successive charges at such station, said means including a carrier having a charge-receiving compartment positionable above said station, a member movable vertically between a normal position to form a bottom for the compartment and a position to form a charge-supporting bottom for said station, and mechanism for concurrently moving said member from its normal position and for discharging the charge from the compartment, said member being yieldably supported. 115

120 48. In packaging machines, wrapping mechanism having an article or charge receiving station, and means for positioning successive charges at such station, said means including a carrier having a charge-receiving compartment positionable above said station, a member movable vertically between a normal position to form a bottom for the compartment and a position to form a charge-supporting bottom for said station, and mechanism for concurrently moving said member from its normal position and for discharging the charge from the compartment, said member being yieldably supported. 125

130

station, and mechanism for concurrently moving said member from its normal position and for discharging the charge from the compartment, said latter mechanism including a plunger device above the carrier for discharging the compartment contents and having means adapted to contact with said member during the discharging operation.

47. In packaging machines, wrapping mechanism having an article or charge receiving station, and means for positioning successive charges at such station, said means including a carrier having a charge-receiving compartment positionable above said station, a member movable vertically between a normal position to form a bottom for the compartment and a position to form a charge-supporting bottom for said station, a yieldable support for said member, and mechanism for concurrently moving said member from its normal position and for discharging the charge from the compartment, said latter mechanism including a plunger device above the compartment for discharging the compartment contents and having means adapted to contact with said member, and an element movable with the plunger and having a lost-motion connection with the member to move the latter bodily during such discharge operation.

48. In packaging machines, wrapping mechanism including a folding channel having a charge-receiving station in advance of and aligned therewith, a rotatable charge carrier positioned above said station and having a compartment adapted to be positioned over such station, said carrier being movable intermittently, a wrapper-receiving chute between said station and channel, an article or charge-advancing plunger movable through said station and chute and into said channel, means for supporting a web of wrapping material, means for feeding said web into said chute when the latter is un-

obstructed by the plunger, and a severing mechanism active on the web to complete the wrapper, said feeding means and severing mechanism being timed to present the completed wrapper in the path of the advancing charge, said severing mechanism including a movable cutting blade, and operative connections between said carrier and said cutting blade for rendering the latter active during movements of the carrier.

49. In machines for wrapping packages, a receiving station for the charge to be wrapped and from which the charge is advanced, a wrapper blank station, a delivery station for the wrapped packet, wrapping mechanism intermediate the wrapper blank station and the packet delivery station, and means for successively advancing the charge into contact with the wrapper blank and through the wrapping mechanism; said wrapping mechanism including a pair of folding channels for combinedly folding the wrapper over the faces of the packet; the end flaps of the wrapper being turned in one of the said channels.

50. In machines for wrapping packages, a receiving station for the charge to be wrapped and from which the charge is advanced, a wrapper blank station, a delivery station for the wrapped packet, wrapping mechanism intermediate the wrapper blank station and the packet delivery station, and means for successively advancing the charge into contact with the wrapper blank and through the wrapping mechanism, said wrapping mechanism including a pair of folding channels for combinedly folding the wrapper over the faces of the packet, one channel being provided with tucking in folders and the other channel being provided with tucking in and end flap folders.

In testimony whereof I have hereunto set my hand.

HILARION DE ESCOBALES.
